DUST RECEPTACLE

Jack E. Duff, North Canton, Ohio, assignor to The Hoover Company, North Canton, Ohio, a corporation of Ohio

Application October 13, 1954, Serial No. 461,983

3 Claims. (Cl. 183—51)

The present invention relates to dust receptacles and more particularly to attaching the receptacle to a suction cleaner and closing the inlet to the receptacle to seal the dust therein prior to discarding the receptacle.

An object of the invention is to provide a disposable paper dust receptacle for a suction cleaner. Another object is to provide a dust receptacle having an adhesive for removably attaching the receptacle to a cleaner. A further object is to provide a dust receptacle having an adhesive for removably connecting the aperture in the receptacle with the inlet of a suction cleaner. Still another object is to provide a seal for the inlet aperture in a dust receptacle to prevent escape of collected dirt upon removing the receptacle from a cleaner. A further object is to provide a dust filtering receptacle having an adhesive for removably attaching the receptacle to the cleaner and also for sealing the inlet aperture in the receptacle prior to discarding the latter. Other objects and advantages of the invention will become apparent from the following description and drawings wherein:

Figure 1 is a section along the line 1—1 of Figure 2 showing the suction end of a cleaner casing.

Figure 2 is a section along the line 2—2 of Figure 1.

Figure 3 is a perspective view of the dust receptacle with the inlet closed, and

Figure 4 is a perspective view of the dust receptacle showing the inlet uncovered for insertion in the cleaner casing.

The embodiment of the invention herein disclosed comprises a dust receptacle 10 arranged within a cleaner casing 11, only partly shown, provided with supporting skids 12 and an unshown suction creating motor-fan unit. At the front end of the casing 11 is an L-shaped annular member 13 attached by screws 14 to the casing and having an end flange 15 projecting inwardly of the casing and defining an opening 16 for inserting the bag 10 into the casing 11. An end cap 17 is hinged at 18 to the casing 11 and has spaced inner and outer walls 19—20 respectively, and a tubular member 21 extends between the walls and is provided with an inner end 22 projecting inwardly of the casing flange 15 into a chamber 23 occupied by the bag 10. The outer end of the tube 21 has a flanged collar 24 which receives one end of an unshown hose provided with a suitable surface cleaning nozzle for conveying dirt-laden air into the bag 10. A clamp 25 is mounted on the casing 11 and has an end 26 engaging the end cap 17 to lock the latter to the casing.

The bag 10 has a rectangular portion 27 formed of filter paper to remove the dirt from the incoming dirt-laden air stream and includes opposite walls 28, side walls 29, a bottom wall 30, and a top wall or end plate 31. The top wall 31 is of relatively stiff material and is glued to an annular exterior flange 32 on the bag, and has a marginal flange 33 projecting beyond the walls of the bag 10.

The bag 10 is secured within the chamber 23 by an

2

annular resilient member 34 mounted in a recess 35 of the cover inner wall 19 and bears against the bag flange 33 to seat the latter against the casing flange 15 when the cover 17 is locked in place by the clamp 25. The walls 28, 29 and 30 of the bag 10 are flexible and lined to be folded flat with the end plate 33 folded along a side wall of the bag for ease in storing and packaging.

Disposed centrally of the end plate 31 is an inlet aperture 36 which receives the inner end 22 of the inlet tube 21 to convey dirt-laden air into the bag 10. The exterior surface of the end plate 31 adjacent the aperture 36 is provided with a pressure sensitive adhesive or gummed surface 38 between the lines 39 and 40 as shown in Figures 3 and 4. The exterior surface of the end plate 31 is covered with a paper sheet 42 having spaced scored lines 43—43 for removing a tape portion 44 which normally covers the adhesive area 38 around the bag aperture 36. In order to uncover the aperture 36 the end 45 of the tape 44 is grasped by the operator to tear the tape 44 along the lines 43—43 to the line 46 as shown in Figure 4. When the tape 44 is peeled back as in Figure 4 the adhesive area 38 is exposed and is adapted to receive a surface 46' of a sealing ring 47 on the cover wall 19 about the tubular end 22 to provide an air tight seal between the bag aperture 36 and the inlet tube 21.

When it is desired to place the bag 11 in the cleaner casing the clamp 25 is unlatched and the cover 17 is rotated about the hinge 18 to its open position to expose the casing flange 15. The end 45 of the tape 44 is then grasped by the operator to tear the tape 44 along the lines 43—43 to the position shown in Figure 4 to thereby uncover the bag aperture 36 and the adhesive area 38. The bag is then inserted in the chamber 23 with the flange 33 resting on the casing flange 15, and the peeled portion of the tape 44 is arranged between the bag wall and the casing wall as indicated at 48 in Figure 1. Upon pivoting the cover 17 to its closed position the tubular end 22 passes through the bag aperture 36 into the bag and the surface 46' of the resilient sealing member 47 bears against the tacky surface 38 on the mounting plate 31 to prevent passage of air between the exterior of the tube 22 and the aperture 36. The resilient member 34 also bears against the bag flange 33 to secure the bag within the casing 11. Thereafter a hose is attached to the collar 24 and dirt-laden air is conveyed to the bag 10 which separates and collects the dust from the air stream.

When the bag 10 must be replaced the cover 17 is pivoted to its open position and during such movement the resilient locking member 34 releases the bag supporting flange 33 from the casing flange 15 while the sealing ring 47 remains attached to the bag so that the latter is moved partly through the opening 16 while the cover 17 is being shifted to its open position. The operator then grasps the peripheral edge 50 of the bag end plate 31 and pulls the adhesive surface 38 away from the sealing ring 47 to disconnect the bag from the cover 17 and permit complete removal of the bag from the casing 11. The sealing tape 44 is then replaced along the lines 43—43 to cover the aperture 36 and prevent escape of dirt, thereafter the bag can be carried to a waste basket or destroyed without danger of the dirt leaking from the bag.

While I have shown and described but one embodiment of my invention, it is to be understood that this embodiment is to be taken as illustrative only and not in a limiting sense. I do not wish to be limited to the particular structure shown and described but to include all equivalent variations except as limited by the scope of the claims.

I claim:

1. A dust collecting receptacle for a suction cleaner having a receptacle supporting member and an inlet tube for dirt laden air, said receptacle comprising a body having a wall portion provided with an opening for connection with the inlet tube, a mounting member attached to said wall portion and having means engageable with the supporting member to position the receptacle in the cleaner, tape means secured to said receptacle and overlying said wall portion and having a portion of greater area than said opening adapted to be partly stripped to uncover said opening for said connection to the cleaner inlet tube, the unstripped portion of said tape means being permanently secured to said receptacle and retaining said tape means on said receptacle for replacement of said stripped portion to again cover said opening and prevent escape of dust from said receptacle.

2. A dust collecting receptacle as described in claim 1, and adhesive means on said wall portion engageable with the inlet tube to secure said opening thereto.

3. A dust collecting receptacle as described in claim 1, and adhesive means to secure said stripped portion of said tape to said wall portion upon replacement of said stripped portion to again cover said opening.
